A. J. LA FAY.
HEATING APPARATUS.
APPLICATION FILED AUG. 16, 1920.

1,391,839.

Patented Sept. 27, 1921.

UNITED STATES PATENT OFFICE.

ARTHUR JOSEPH LA FAY, OF TORONTO, ONTARIO, CANADA, ASSIGNOR OF ONE-HALF
TO HUGH R. TUDHOPE, OF ORILLIA, ONTARIO, CANADA.

HEATING APPARATUS.

1,391,839.

Specification of Letters Patent. Patented Sept. 27, 1921.

Application filed August 16, 1920. Serial No. 403,974.

To all whom it may concern:

Be it known that I, ARTHUR J. LA FAY, of the city of Toronto, in the county of York, Province of Ontario, Canada, a subject of the King of Great Britain, have invented certain new and useful Improvements in Heating Apparatus, of which the following is a specification.

The present invention relates to heating apparatus and the principal object contemplates the provision of means for utilizing to a maximum degree, the caloric comprising the products of combustion, as an auxiliary to the heat radiating function of the furnace for increasing the efficiency of the same.

A further object of the invention is to provide a heating apparatus, wherein a maximum amount of the caloric is derived from a given quantity of fuel for effectively heating a given space.

In general the principle of operation involved in the construction of my improvements is to lead the hot products of combustion in a stream moving continuously between an outer casing and the casing of the furnace and then lead them through a special flue or flues to the smoke pipe.

I attain my object by means of the constructions hereinafter more specifically described and illustrated in the accompanying drawings in which—

Figure 1 is a longitudinal sectional elevation of the heating apparatus embodying my improvements.

Fig. 2 is a vertical section on line 2—2 of Fig. 1 looking in the direction of the arrows.

Fig. 3 is a horizontal section in plan, of a slightly modified form of my device; and

Fig. 4 is a fragmental vertical section taken at the rear of Fig. 3.

In the drawings like numerals of reference indicate corresponding parts in the different figures.

Referring to Figs. 1 and 2 of the drawings, 1 is a fluid heating furnace of ordinary construction with vertical sections, though my invention is, applicable to furnaces of the horizontal sectional type. This heater, it will be seen is of the type in which internal flues are provided and spaces for the fluid to be heated externally bounded by the walls of the furnace and surrounding the

internal flues. 2 is the smoke collar or exit of the furnace. The furnace is surrounded by an external casing 3 of metal or some refractory material and preferably the arrangement of the external casing is such that the front of the boiler with its doors is exposed. The external casing is preferably rectangular in plan and is spaced from the sides and top of the furnace as indicated in Figs. 1 and 2. The spacing between the external casing and the casing of the furnace forms substantially a passage for the products of combustion into which a smoke exit for the furnace opens.

In the arrangement illustrated in Figs. 1 and 2, a chamber 4 is formed at the rear part of the furnace and is separated from the rear jacket space 5 by a partition 6. The chamber 4 is provided with the usual smoke pipe 7 leading to the chimney. In the partition 6 is formed an opening 8 controlled by the sliding damper 9.

In the space between the side walls of the furnace 1 and the external casing 3, are located the alternate baffle plates 10 and 11 preferably of metallic construction. The plates 10 are of substantially inverted U-configuration and extend transversely around the greater part of furnace 1, the top or arch portion 12 being secured to the inner surface of the top plate 13 of the casing 3. The vertical leg portions 14 of the baffle plates 10, have edge engagement with the inner and outer walls of the casing 3 and furnace 1.

The lower ends of the vertical leg portions of the baffle plates 10 are spaced from the bed 15 of the furnace to provide a series of openings 16, 17 and 18. Interposed between plates 10 are the baffle plates 11, which have their lower ends suitably connected to the furnace bed 15. The plates 11, are formed in two sections the upper arched portions 19 of which are connected to the angularly disposed partition plates 20. The upper arched portions 19 of the plates 11 are spaced apart and form flue spaces, 21, but in other respects the said plates are of the same configuration as plates 10, and serve with the latter to effectively baffle the caloric current in its passage through the heating apparatus.

Resultant of positioning the angularly disposed plates 20 in the manner stated, two

triangular return flues 22 and 23 are formed the function of which will hereinafter be more fully described.

When the damper 9 is opened, the products 5 of combustion pass upwardly through opening 8 into chamber 4 and out through the chimney pipe 7.

When, however, it is desired to utilize the maximum calorific value of the products 10 of combustion, the damper 9 is adjusted to close the exit opening 8, which action will cause the products of combustion to be directed into the rear jacket space 5, the products of combustion by reason of the 15 closing of the damper space 8, will pass through the rear space 16 between the furnace bed 15 and rear baffle plate 10 and thence will circulate upwardly in the space between the rear baffle plates 10 and 11, at 20 each side of the furnace proper. As the upper arched ends 19 of baffle plates 11 are spaced apart at the top of the furnace and form the spaces 21, the products of combustion will pass through these spaces 21, 25 around the confronting edges of the said plates 11 and downwardly into the spaces between the said plates 10 and the next succeeding baffle plate 10. The last mentioned plate 10 being spaced from the bed provide 30 the openings 17, through which the products of combustion will pass upwardly into the space between the plates and the next preceding plates 11. Then the products of combustion pass into the space between the 35 arched ends 19 of the plates 11 and downwardly through the space between the plates 11 and the plate 10. Upon passing through the openings 18 at the lower end of the front baffle plate 10, the products of combustion 40 pass upwardly into the return flues 22 and 23, which latter extend the entire length of the external casing at the top thereof and resultantly the products of combustion, deprived of their calorific value, due 45 to their contact with the outer walls and top of the furnace, will pass into the rear chamber 4 and out through the pipe 7 to the chimney.

In this manner, the products of combustion 50 in consequence of the novel arrangement of the baffle plates 10 and 11, are circulated entirely around the sides and top of the furnace and consequently, the calorific quantity is utilized to a very marked degree.

55 By this construction, the products of combustion are utilized as an auxiliary heating medium and coöperates with the furnace in developing a maximum degree of heat for the generation of steam in the coils.

60 In the modification illustrated in Figs. 3 and 4, I inclose the furnace 24 within a metallic external casing 25 of similar construction as that of the preferred form, with the exception that a chimney outlet collar 65 26 is arranged on the top of the casing 25

immediately above the chamber 27. A partition 28 separates the chamber 27 from the rear jacket space 29 and said partition 28 is formed with an opening 30 which is regulated by a sliding damper 31, which like 70 the damper 9 of the preferred form, is supplied with a handle rod 32. A smoke collar 33 opens into the rear jacket space 29.

A plurality of baffle plates 34 are positioned in an alternate relation with the baffle plates 35, within the space between the furnace and casing 25. The baffle plates 34 are formed at their upper part with arched shaped end portions 36 which extend partly over the top or crown of the furnace, 80 and are connected to the transverse partition plates 37 and 38. These plates 37 and 38 are connected at the rear to the partition 28 and the front ends of the partitions 37 and 38, are connected to the front baffle plates 34 85 and are spaced from the front wall of the casing. The baffle plates 34 at their lower ends are spaced from the base of the furnace to provide openings similar to openings 16, 17 and 18 of the preferred form, 90 while the baffle plates 35 have their lower ends suitably secured to the furnace base and extend only part way up the sides of the furnace, as illustrated in Fig. 4.

By the provision of the partitions 37 and 38 a central flue 39 is formed which extends from the front of the casing to the chamber 27 at the rear.

When the damper 31 is open the products of combustion circulate upwardly through opening 30 into chamber 27 and out through the outlet collar 26 to the chimney.

When the damper is closed, the products of combustion pass downwardly from the smoke collar 33 into the jacket space 29. 100 The products of combustion containing the calorific pass through the spaces between the lower end of the rearmost baffle plates 34 and furnace bed and then upwardly over the tops of the short baffle plates 35. Thence the 110 combustion currents pass downwardly and through the opening under the next preceding baffle plate 34. This circulation is continued toward the front of the casing and furnace, where the products of combustion pass up into the front passage 40 and rearwardly through the flue 39 to the chamber 27 to the outlet collar 26.

115 In this manner, the products of combustion in its passage through the casing, is, by reason of the baffle plates, is forced to circulate in channels, which bring the same in contact with the walls of the furnace proper. Resultantly the calorific by contact with the furnace walls, serves as an auxiliary heating 120 means for the same and thus the maximum heating function of the furnace is accomplished, resulting in the full utilization of the products of combustion, which otherwise would be lost.

Likewise by the arrangement of dampers 41 in the baffle plates 11, as illustrated in dotted lines in Fig. 1, the products of combustion will have unobstructed passage 5 through the lower part of the casing and will pass upwardly and out through the top of the casing to the chimney exit.

By this novel construction a great economy of fuel is effected and the waste products of 10 combustion is utilized.

Should it be desired, coils could be placed in the return flues 22 and 23 and the water circulating therethrough, will be heated by the products of combustion passing to the 15 chimney.

The use of water coils in the manner stated, would be more particularly adaptable, where the furnace is of the ordinary hot air type, the interior steam or hot water 20 coils being dispensed with.

What I claim as my invention is:—

1. The combination with a fluid heating furnace of the horizontal type provided with internal flues for the products of combustion 25 and spaces for the fluid to be heated externally bounded by the casing of the furnace, of an external casing spaced from the sides and top of the furnace, a smoke outlet at the end of the external casing, depending 30 baffles dividing the space between the furnace and external casing into a plurality of vertical flues, the upper part of said baffles extending over the top of the furnace casing, a plurality of baffles alternately dis- 35 posed between the first mentioned baffles, said last mentioned baffles extending only partly across the top of the furnace casing and forming openings communicating with the flue spaces between the said baffle plates, 40 angularly disposed walls extending between the top of the furnace casing and the top of the external casing, the said walls forming triangular shaped return flues communicat- 45 ing with the vertical flues, a chamber opening into the smoke outlet, a jacket adapted for the reception of the products of combustion from the furnace, a damper controlling the communication between the chamber and jacket, said chamber communi- 50 cating with the return flues and smoke outlet, the upper part of the first mentioned baffles adapted to direct the products of combustion from the jacket to the said return flues and the smoke outlet.
- 55 2. The combination with a fluid heating furnace of the horizontal type including internal flues for the products of combustion

and spaces for the water to be heated, of an external casing spaced from the sides and top of the furnace, a chamber arranged at 60 the rear of said casing, a smoke outlet communicating with said chamber, a jacket disposed below said chamber, the said jacket adapted to receive the products of combustion from the furnace, depending baffles di- 65 viding the space between the furnace and external casing, a plurality of vertical flues, the upper part of said baffles extending over the top of the furnace, a plurality of baffles interposed between the first baffles and hav- 70 ing their upper end extending partly across the top of said furnace, angularly disposed walls arranged in the upper end of said casing and forming return flues communicat- 75 ing with the vertical flues at the front of the casing, and said chamber and the upper ends of said baffles being connected to said walls, and said baffles being adapted to direct the products of combustion from the jacket to the return flues.

3. The combination with a fluid heating furnace, of an external casing spaced from the sides and top of the furnace, the space between the rear end of the furnace and casing forming a chamber and jacket, a damper 80 connection between said chamber and jacket, an outlet connection leading from the chamber, said jacket adapted for the reception of the products of combustion from the furnace, a plurality of baffle plates arranged in 85 the space between the sides and top of the casing and the furnace, baffle plates disposed alternately between the first mentioned plates, and forming vertical flues, the second mentioned plates having their upper ends 90 extending only partly over the furnace top, the lower ends of said plates extending to the furnace bed, and the lower ends of the other of said baffle plates being spaced from the furnace base, a pair of angularly dis- 95 posed plates secured to the upper end of said casing and forming triangular shaped flues extending across the top of said casing, the said flues communicating with the forward vertical flues formed at the front of 100 the casing and with the said chamber and the said baffle plates being adapted to direct the products of combustion from the jacket to the return flues and into the said chamber and outlet.

Signed at Toronto, Canada, this 9th day of August, 1920.

ARTHUR JOSEPH LA FAY.
